UNITED STATES PATENT OFFICE.

FRANKLIN G. NEUBERTH, OF ANSONIA, CONNECTICUT, ASSIGNOR TO EMMA NEUBERTH,
OF ANSONIA, CONNECTICUT.

BUTTON.

Application filed January 18, 1927. Serial No. 161,852.

The invention relates to buttons such as collar or sleeve buttons, or studs and the like; and more especially to a button member of this character which shall be provided with 5 an integral post bearing some ornament at the top, for example, of pearl, shell, stone or a suitable enamel or composition and rigidly maintained in position by the novel holding means afforded.

10 The invention has for its object the manufacture of such buttons from rod material of suitable character and in a simple and expeditious manner so that the buttons may be produced in quantity and at a minimum cost. 15 A further object of the invention is to adequately secure an ornamental tip portion thereto and in manner such that the backing portion of the button proper or post thereof shall be substantially invisible when the button is viewed from the front or top.

To this end, rod sections of the required length are subjected to the action of forming dies by which the diameter of the section is reduced to form the shank or post of the 25 button with holding portion, a lower or base flange provided and a novel backing flange formed at the top to which is then to be secured the ornamental tip portion. The nature of the invention will best be understood, 30 however, when described in connection with the accompanying drawings, in which:

Figs. 1 and 2 indicate the operation of the forming dies with blanks in position.

Figs. 1^a and 2^a show the dies in closed 35 position with the blank formed thereby to the shape indicated.

Fig. 3 is a detail fragmentary sectional view illustrating the manner of applying the tip or head portion to the blank resulting 40 from the various operations.

Fig. 4 is an elevation and part vertical section, and Fig. 5 a plan view of the completed button.

Fig. 6 illustrates a modification wherein a 45 tip is applied to both ends of the post.

Fig. 7 illustrates a further modification showing the application of an enamel or layer of composition to the tip.

Referring to the drawings, 10 and 11 designate 50 respectively the upper and lower members of a forming die which are designed to receive a blank 12 in the nature of short cylindrical sections of rod. The material of this rod may consist of aluminum, aluminum alloy, rolled gold or of such material

as celluloid, etc., which can be readily formed up into the desired shape and is of sufficient plasticity to admit of the further operation required in securing the tip portion. The action of the die halves 10 and 11 is to form 60 the blank 12 into the shape indicated in Fig. 1^a. At this stage, the blank has had its diameter reduced considerably, providing the post portion 13 and the base flange 14 with slight conical recess 15 at the top of the post. 65 The blank in this condition is then brought to the further forming dies comprising the upper and lower members 16 and 17 and the side members 18 and 19, whereby the upper portion of the post 13 is provided with a 70 backing flange 20 and a hollow cylindrical upstanding portion 21 having the edge of its inner rim preferably beveled, as indicated at 22.

The blank at this stage is now in condition 75 to receive the ornamental tip or head 23 which may be built up of metal and suitably covered or may consist of a block of shell, pearl, stone, composition of various kinds, etc., and cut or formed to the shape 80 hereinafter set forth. In order to position securely such ornamental tip to the head of the post 13, the undersurface of said head is under-cut to provide a more or less annular and conically shaped depression 24 of 85 sufficient width to receive the wall of the hollow cylindrical upstanding portion 21 and of sufficient depth to fully accommodate said portion, so that the under-surface of the tip 23 may abut the outer surface 90 of the flange 20. This is accomplished by forcing the tip 23 to the body portion of the button, the material composing the up-standing portion 20 thereof being preferably somewhat softer than the tip portion 95 whereby the former will be forced into and fill the under-cut cavity 24, being assisted in sliding therein through the beveling at 22. It will be noted that the upper portion 100 of said upstanding part 21 is thereby bent over, positively securing the said tip to the body portion and the diameter of which tip is such also as to fully cover the flange 20.

This will thus entirely conceal the latter and give the impression, when viewed from 105 the top of the tip, of being composed entirely of the more or less expensive shell or other material which has been thus secured.

It will be appreciated, also, that for certain purposes, as in the case of links or the 110

like, a tip portion may be provided at both ends of the post, the lower or base flange 30 then being reduced in diameter so as to be equal to that of the upper flange 31 and said flange 30 being provided also with an upstanding portion 32 similarly to the upstanding portion 33 associated with the flange 31. The ornamental tips 34 and 35 are then to be secured to each upstanding portion as hereinbefore described and abutting the corresponding flanges 30 and 31.

Furthermore, a metal tip 36, Fig. 7, having an enamel coating 37 provided thereon may likewise be attached to one or both ends 15 of the post; and in such embodiment it is desirable to bring the coating slightly over the undersurface of the metal tip portion so that when the same is secured against the

flange no raw metal of the cap will be exposed.

20

I claim:

A button of the character described, comprising a solid shank or post having a hollow holding member extending therefrom at one end with an integral backing flange 25 surrounding the said holding member substantially at the base of its hollow portion, and an ornamental tip member undercut to receive the hollow holding member, having a forced fit therewith and its under face 30 contacting with the outer face of the said backing flange to substantially cover the same, whereby strain on said ornamental member is obviated in the use of said button.

In testimony whereof I affix my signature.

FRANKLIN G. NEUBERTH.
